US0D1067325S

(12) **United States Design Patent** (10) **Patent No.:** **US D1,067,325 S**
(45) **Date of Patent:** **** Mar. 18, 2025**

(54) **CARD CASE**

(71) Applicant: **Shenzhen Youlequ Trading Co., Ltd.**,
Shenzhen (CN)

(72) Inventor: **Meng Zhou**, Shenzhen (CN)

(73) Assignee: **Shenzhen Youlequ Trading Co., Ltd.**,
Shenzhen (CN)

(**) Term: **15 Years**

(21) Appl. No.: **29/962,247**

(22) Filed: **Sep. 11, 2024**

(51) **LOC (15) Cl.** **21-01**

(52) **U.S. Cl.**

USPC **D21/392**

(58) **Field of Classification Search**

USPC D21/392; D3/299, 302, 294; D6/683.1
See application file for complete search history.

(57) **CLAIM**

The ornamental design for a card case, as shown and described.

DESCRIPTION

FIG. 1 is a top perspective view showing the card case in a split state, showing my new design;

FIG. 2 is a bottom perspective view showing the card case in a split state;

FIG. 3 is a front view showing the card case in a split state; FIG. 4 is a rear view showing the card case in a split state; FIG. 5 is a left side view showing the card case in a split state;

FIG. 6 is a right side view showing the card case in a split state;

FIG. 7 is a top view showing the card case in a split state;

FIG. 8 is a bottom view showing the card case in a split state; FIG. 9 is a top perspective view showing the card case in a combined state; and,

FIG. 10 is a front perspective view showing the card case in other split state.

The evenly spaced broken lines in the drawings illustrate the portions of the card case, which form no part of the claimed design. The dot-dash-dot broken lines represents claimed stitching.
